UNITED STATES PATENT OFFICE.

JOHN DEGNAN, OF CHICAGO, ILLINOIS.

DOWN-SPOUT HEAD.

1,180,018.

Specification of Letters Patent. Patented Apr. 18, 1916.

Application filed May 17, 1912. Serial No. 697,992.

To all whom it may concern:

Be it known that I, JOHN DEGNAN, a citizen of the United States, residing at Chicago, in the county of Cook and State of Illinois, have invented new and useful Improvements in Down-Spout Heads, of which the following is a full, clear, concise, and exact description, reference being had to the accompanying drawing, forming a part of this specification.

My invention relates to down-spout heads.

In the large buildings of the present day the roofs are generally made flat and the water is drained off by means of one or more down-spouts extending through the roof and down in through the building, either to storage tanks, if it is desired to use the water, or to suitable waste pipes.

It is one of the objects of my invention to provide a down-spout head which shall be of substantial construction, comparatively easy to install, efficient in operation, of small cost, and which shall be able to withstand for long periods of years the wear and tear of the elements and the more or less careless treatment of those having occasion to be in their vicinity.

For the purpose of disclosing my invention I have illustrated one embodiment thereof in the accompanying drawings, in which—

Figure 1 is a sectional view of the spout-head showing the same in position; and, Fig. 2 is a top plan view of the spout-head.

In the embodiment illustrated, the down-spout 1 is shown as coming up to the roof 2. These roofs are usually formed of tile and at the point where it is desired to take off the water they are sloped downward slightly toward a common center so that the water will run toward this point. The down-spout head is adapted to be attached to the down-spout 1 and comprises a base 3 and a cover or cap 4. The base 3 of cast iron preferably takes the form of a hollow truncated cone with its top turned downwardly and at its lower end is provided with a screw-threaded opening 5 adapted to be threaded onto the top of the down-spout 1. This opening is provided with a shoulder 6 which is preferably as wide as the pipe is thick, to form a smooth and unobstructed opening into the pipe. The top of the base is provided with an annular flange 7 to which is adapted to be secured the strainer cap 4 of cast brass is

preferably semi-spherical in shape and is provided with a central opening 8 and a plurality of slots 9. An annular flange 10 is also secured to the cap and by means of the flange it is secured to the base 3 by bolts 11 passing through the flange 10 and the flange 7. Due to the fact that the inclinations or slopes of the roof vary on different roofs and in order that a water-tight lead may be given to the head I clamp between the flanges 7 and 10 a flashing 12 which is adapted to be extended up underneath the roof covering the desired distance, the roof covering being adapted to come down and lie flush with the flange 10. This flashing may take any form so far as material is concerned. It may be of sheet copper, sheet steel, sheet rubber, or any desired material. Preferably, however, it is of some flexible material, so that it may be shaped to fit the roof at the point where the spout head is mounted.

In placing the head in position the base member is inserted in a suitable opening in the roof, and after being screwed down tight on the top of the down-spout pipe is filled in around with cement to hold the same in position. The flashing extends out under the roof covering proper and makes a water-tight joint at the meeting flanges, so that the water will not work down along the sides of the base. The cap is screwed tight on the top of the base.

While I have shown and described for the purpose of disclosing my invention one form which the same may take, it will be understood that my invention may be embodied in other forms and made of other materials and that it may be changed without departing from the spirit of my invention as set forth in the appended claim.

Having thus described my invention, what I claim as new and desire to secure by Letters Patent, is:

The combination with a down spout comprising a vertical pipe section having an externally threaded upper end, of a down spout head comprising a funnel shaped member of cast metal having an internally threaded lower end screwed onto said threaded upper end, the inner surface of said funnel at its lower end being substantially continuous with the inner surface of said pipe, said funnel shaped member having an annular flange at its upper end and a substantially hemispherical cap fitting on top

of said funnel member, the inner surface of said cap being substantially continuous with the inner surface of said funnel member, said cap having a flange opposite to the flange on the funnel and being provided with a series of slots extending from the central portion of said cap substantially to the cap flange, the combined area of said openings being equal to the cross sectional area of the lower end of the funnel, and

screws extending through said flanges for securing them together.

In witness whereof, I have hereunto subscribed my name in the presence of two witnesses.

JOHN DEGNAN.
